UNITED STATES PATENT OFFICE.

AXEL JULIUS LAURITS LASSEN, OF FREDERIKSBERG, NEAR COPENHAGEN, DENMARK.

MACHINE FOR MAKING AND APPLYING CAPS ON BOTTLES AND THE LIKE.

Specification of Letters Patent. Patented Nov. 26, 1918.

1,285,745.

Application filed December 15, 1916. Serial No. 137,122.

To all whom it may concern:

Be it known that I, AXEL JULIUS LAURITS LASSEN, a citizen of the Kingdom of Denmark, residing at No. 5 Aa Boulevard, Frederiksberg, near Copenhagen, in the Kingdom of Denmark, have invented certain new and useful Improvements in Machines for Making and Applying Caps on Bottles and the like, of which the following is a specification.

The well known bottle caps consisting of a metal disk with an inner lining or packing disk (washer) of cork, pasteboard, or the like, have hitherto been made by cutting or stamping out the metal disk simultaneously with the washer by means of a die, so that the two cut or stamped parts have the same size; when applied to a bottle a cap thus produced will have its washer between the metal disk and the neck of the bottle, thereby to a certain degree impeding a tight and reliable connection between the cap and the bottle. In order to avoid this difficulty, the two disks have been made separately, in some cases, the washer being given a smaller diameter, corresponding to that of the bottle mouth. This latter method makes it necessary to place the packing disk or washer in the metal disk by means of a special operation, which takes time and entails extra expense.

The present invention has for its object to obviate the disadvantages connected with the methods referred to above. According to my invention the bottle cap is made and applied in a continuous series of steps forming virtually a single operation, viz: First the metal disk and thereafter the washer is cut out by a die, the washer being given a smaller diameter than the metal or capsule disk and being placed centrally on the latter, after which the edge of the capsule disk is bent over and finally the finished bottle cap is automatically carried to one or more mechanisms which are actuated by the die-mechanism and apply the cap securely on the mouth and around the neck of the bottle.

In order to more fully explain my said invention the same will be described in detail with reference to the drawing, which, by way of example, shows an embodiment of a machine for performing the process in question. The machine is represented in a side view showing the cutting-die mechanism

and the cap-applying mechanism, partially in section.

In a casing 1 secured to the machine frame, which casing is closed at the top by a screwed-on cylindrical head or cap 2, a piston 3 is movable up and down. The piston 3 is connected at the top with the tubular cutting-piston 4 proper, the opening of which is flush with the bore 5 in the piston, and in this cylindrical channel there is disposed a rod or stop 8, which is held stationary in the casing 1 by means of a pin 9. To enable the piston to move lengthwise, it is made with a slot 10 through which said pin 9 extends. The stop 8 has at the top an oblique surface 11 in registry with the lower limit-surface of an oblique chute 12 in the wall of the casing 1.

In the top of the casing 1 and in the cylindrical head 2, there are two diametrically opposite, horizontal slits or openings 13 through which the strip of metal from which the capsule disks are cut is passed in the well-known manner, and above these openings there is disposed a cutting-ring 15 held in place by a ring-shaped nut 14.

In the cylindrical head 2 a tubular piston 16 actuated by a spring 17 is movable up and down around a rod or mandrel 18 adjustably screwed into the said head, the lower end of said mandrel forming a punch for cutting out the packing disk or washer. In the lower end of the piston 16 a cutting-ring 20 is held fast by means of a ring-shaped nut 19, said cutting-ring having an inner diameter corresponding to the outer edge of the bottle mouth, and above this cutting-ring the piston is furnished with a bore 21 of sufficient diameter to leave an annular space around the lower end of the mandrel 18. The bore 21 corresponds to two diametrically opposite, horizontal slots or openings 22 in the head 2, through which the strip of pasteboard, or the like, from which the packing disks or washers are cut, is passed in the well-known manner.

The chute 12 communicates with a tube 23 secured to the outer wall of the casing 1, and the lower end of this tube extends slidably into a corresponding tube 24.

The lower end of the piston 3 is forked, and between the forks there is disposed an axle-pin 26 which carries a roller 25. Below the latter there is disposed the horizontal

drive-shaft 27 of the machine, carrying a cam 28, which actuates the roller 25 and also a roller 29 disposed below said shaft. The roller 29 is disposed on an axle-pin 30, which is journaled in the upper, forked end of a tube 32, movable up and down in a guide 31 secured to the machine frame. The axle-pins 26 and 30 are connected by a spring 33.

10 Into the lower end of the tube 32 is screwed a capping die 34, which surrounds a piston 36 under the influence of a spring 35, and carries a mouthpiece 37 adapted to fit the neck of the bottle, which mouthpiece 15 is connected with the tube 24.

The operation of the machine is as follows:

When the drive-shaft 27 is turned in the direction indicated by the arrow, the cam 28 will carry the piston 3, 4, upward toward the metal strip passed through the openings 13, whereby the metal strip is pressed up against the cutting-ring 15, with the result that a metal disk is cut out. As the 25 piston continues to rise, the metal disk is carried through the cutting-ring 15 up to the lower surface of the cutting-ring 20, and the piston 3, 4, now presses the cut metal disk against this cutting-ring, thereby pushing the piston 16 upward, so that the pasteboard strip passed in through the openings 22 is pressed by the cutting-ring 20 up against the piston-shaped end of the mandrel 18. Thus there is cut a packing-disk 35 or washer which lays itself centrally on the metal disk, while the latter, during the continued upward movement of the pistons 3, 4, and 16, is pressed up against the mandrel 18. During the last part of the upward 40 movement of the piston 3, 4, the edge of the metal disk will be bent up around the mandrel 18, when the ring 4 rises to a position in which it surrounds the lower end of this mandrel, so that the cap is finished. On its 45 upper surface, the piston 4 has millings 38, which mark the bent-over edge of the metal disk so that it is given regular flutes or corrugations.

On the ensuing downward movement of the piston 3, 4, the spring-actuated piston 16 will strip the finished cap or capsule off the mandrel 18, so that the capsule follows the piston 3, 4, down until the oblique surface 11 on the stop 8 engages said capsule. 50 Then the capsule will be loosened from the inner cavity of the piston ring 4, and will slide along the surface 11 through the chute 12 and down through the tubes 23, 24, until, with its concave side turned downward, it 55 lies in the mouthpiece 37 under the piston 36.

On the continued turning of the cam 28, the roller 29 will now be so actuated that the tube 32, and with it the capping die 34, with the attached mouthpiece 37, will be carried 60 down over the bottle, against the mouth of

which the capsule is pressed firmly by the spring-pressed mandrel 36, whereby the capsule will be caused to close tightly around the neck of the bottle, the conical cavity in the capping die 34 being pressed down over 70 the bottle mouth. Then, during the further turning of the cam 28, the piston 36 is again lifted, while the spring 33 will still hold the roller 29 against the face of the eccentric, and the operations described above will 75 then be repeated.

The tube 24 may have several branches, each of which leads to its individual mouthpiece, so that several bottles may be provided with caps simultaneously, in which 80 case the piston 3, 4, must, however, be moved by a separate cam, or the like, on the drive-shaft, and at a higher speed than the pistons which put on the caps.

I claim:

1. In a machine for making bottle caps, a casing, a mandrel extending lengthwise within said casing, a tubular spring-pressed piston surrounding the mandrel and movable lengthwise in said casing, an annular cutter 90 secured to said piston adjacent to the free end of the mandrel, another annular cutter, of larger diameter, secured to the casing at a greater distance from the free end of the mandrel than the first-named cutter, and a 95 punch movable toward the free end of the mandrel through the cutter of larger diameter and against the spring-pressed piston to first cut a disk of material by the cooperation of the punch with the large-diameter 100 cutter, then cut a smaller disk of material by the cooperation of the cutter on the piston with the mandrel, and finally bend the projecting edge portion of the larger disk around the edge of the smaller disk. 105

2. In a machine for making and applying bottle caps, a casing, a stop therein, a tubular punch surrounding said stop and movable lengthwise thereof, means, coöoperating with said punch during its working stroke, 110 for producing a bottle cap, the said stop being provided, at the end nearest said means, with an oblique surface to deflect the cap laterally as it is carried along by the retreating punch, a chute to receive the cap 115 thus deflected, and bottle cap applying mechanism to which said chute leads.

3. In a machine for making and applying bottle caps, a casing, two longitudinally aligning spaced rods in said casing, a tubular 120 punch surrounding one of said rods and movable lengthwise thereof, a stationary annular cutter located between the two rods and coöoperating with said punch, the opening of said cutter being wider than the said punch so that the latter may pass through said cutter, a piston surrounding the other rod and movable lengthwise thereof, said piston being provided with an annular cutter adapted to coöperate with the last named 125 130

rod, the opening of the last-named cutter being smaller than said punch so that the latter cannot pass through said cutter but will force it toward said last-named rod, the 5 first-named rod having an oblique surface at the end facing the other rod, to deflect the cap laterally as it is carried along by the re-treating punch. 30

10 4. In a machine for making bottle caps, a casing, two longitudinally alining spaced rods in said casing, a tubular punch surrounding one of said rods and movable lengthwise thereof, a stationary annular cutter located between the two rods and co-operating with said punch, the opening of 15 said cutter being wider than the said punch so that the latter may pass through said cutter, and a piston surrounding the other rod 20 and movable lengthwise thereof, said piston being provided with an annular cutter adapted to coöperate with the last named rod, the opening of the last-named cutter being 25 smaller than said punch so that the latter cannot pass through said cutter but will force it toward said last-named rod, the first-named rod having an oblique surface at the

end facing the other rod, to deflect the cap laterally as it is carried along by the re-treating punch. 35

5. In a machine for making and applying bottle caps, a reciprocating punch and means coöperating therewith for producing a bottle cap, a reciprocating capping die in longitudinal alinement with the said punch, means located between said punch and said die and arranged to operate both of them, and means for conveying the caps from the cap-producing mechanism to said capping die. 40

6. In a machine for making and applying bottle caps, a reciprocating punch and means coöperating therewith for producing a bottle cap, a reciprocating capping die in longitudinal alinement with the said punch, an operating cam located between said punch and said die, and a spring connecting the punch with the die and tending to draw them toward each other and against said cam. 45

In testimony that I claim the foregoing as 50 my invention I have signed my name in presence of two subscribing witnesses.

AXEL JULIUS LAURITS LASSEN.
